SHEETING MACHINE

Sander Debus, Hastings, Nebr., assignor to U. S.
Slicing Machine Company, a corporation of
Indiana

Application April 8, 1935, Serial No. 15,206

7 Claims. (Cl. 242—55)

My invention relates to sheeting machines, its primary object being the provision of a device which reels sheet material from the roll and into a convenient form for cutting the material into sheets of the desired length.

Another object of the invention is the provision of a simplified structure for adjusting the reel in order to obtain sheets of the desired lengths.

Another object of the invention is the provision of connections between the bars and the arms of the reel for preventing binding action when the material is being wound on the reel.

Another and a very important object of the invention is the provision of a knife guide on the reel so that the material may be most effectively cut into sheets of the desired length.

I also have in view the provision of a clamp for securing the material at its end edge to the reel, the clamp being operative in a manner so that the reel may be turned in either direction to unroll the material from any one of a plurality of rolls which are supported on the frame of the machine.

Having in view these objects and others which will be pointed out in the following description, I will now refer to the drawing, in which

Figure 1 is a view in perspective of the entire reel.

Figure 2 is a detail plan view showing the relations of the reel arms and knife guide to the spindles.

Figure 3 is an enlarged view in vertical section showing particularly the relation between the bars and the clamps which secure the bars to the reel arms.

Figure 4 is an enlarged perspective view of the clamp which I employ for securing the roll material at its free end edge to the reel, a fragment of the spreader bar being also shown.

Figure 5 is a view in side elevation of the reel in slightly modified form in position on its frame, the frame being shown in conventional form.

The frame 10 of the machine is shown in very conventional form in Figure 5. This frame may be varied in numerous ways, its function being primarily to support the reel at a convenient height and to support one or more rolls of the material which is to be reeled and cut into sheets.

The reel assembly is shown in Figure 1. It includes arms 11 projecting radially from cylindrical members 12 which terminate in the spindles 13. These arms 11 may be provided with calibrations as shown in Figure 2 in which the numerals 1 and 2 may indicate distances from the axis of

rotation. The arms 11 pass through and extend to both sides of the cylindrical members 12 to which they are secured by means of set screws 14. The bars 15 span the distance between the end portions of the arms 11, these being the bars on which the sheet material is reeled. Clamps 16 are employed to connect the arms 11 and the bars 15. These clamps are split as shown in Figure 3 so that a very firm clamping action may be obtained by tightening the screws 17. The ends of the bars 15 are reduced to fit loosely into sockets 16' in the clamps 16 in the manner shown in Figure 3. This loose connection is for the purpose of preventing binding action especially after a number of layers of the sheet material has been reeled. At the beginning of the reeling operation there is very little difficulty from binding but the tension increases rapidly with the number of layers on the reel and it is when the tension increases that the loose connection of the bars 15 with the clamp 16 compensates to a very large extent for the binding action.

The spacer or spreader 18 is firmly secured at its opposite extremities to the two cylindrical members 12. This spreader functions not only to spread the two layers of sheets on the reel but it serves also as a knife guide and as a support for the paper clamp. It consists of two plates 19 and 20 of uniform width and an intermediate plate 21 having a width less than that of the plates 19 and 20. The spreader may be either laminated as shown in Figures 1, 2, and 4 or of integral construction as shown at 18' in Figure 5. A clamp 22 is hingedly secured to one of the plates 19 or 20 by means of hinges 23. The clamp further includes a screw 24 passing through a suitable aperture in the clamping member 22 and into either of the plates 19 or 20.

In use the material is unrolled from a roll 25 and its free edge is secured by means of the clamp 22. The reel is then turned by hand by means of the crank 26 so that the material is wound on the reel. Where only one roll is employed, one clamp 22 will serve the purpose as the rotation of the reel will always be in the same direction. When a number of rolls are supported on the frame 10, a second roll 27 may be in position such that it will not readily reel but this difficulty may be overcome by the use of clamps 22 on both sides of a spacer. The spacer may be the spacer 18 comprising the several parts as shown in Figures 1, 2 and 4, or it may be integral as indicated at 18' in Figure 5.

My sheeting machine is designed for use primarily with Cellophane. Great difficulty is en-

countered in cutting this material because of its relative hardness and because of its peculiar curling qualities. A shear action is wholly unsatisfactory and the number of layers which can be thus cut is very limited. For this reason I provide a novel form of cutting guide which will function with the blade of an ordinary jack knife or any other suitable cutting blade. The plate 21 is narrower than the plates 19 and 20, thus affording a channel between the plates 19 and 20 for the passage of a cutting blade, this channel being underneath the layers of Cellophane or other sheet material. A double guide is thus provided so that the knife cannot slip to cut the material with irregular edges. While Cellophane is very hard and thus resists shear action, it is sufficiently brittle especially when under tension to respond readily to the sliding knife action of a cutting blade sliding in the groove between the plates 19 and 20 of the spacer 18.

The reeling of the material is accomplished in a manner indicated in Figure 5. The operator merely turns the crank handle 26 until the desired number of layers of the material have been reeled. This operation is stopped with the handle 26 directed downwardly and with the channel between the plates 19 and 20 directed upwardly. A cutting blade is then inserted in the channel at its end and is then drawn through the channel from end to end of the web spacer 18, thus slitting all of the layers of the material on a straight line. The material will then be in the form of sheets of substantially uniform dimensions. The width is of course governed by the width of the material in the roll. Any width not exceeding the length of the web spacer 18 may be reeled. The length of the sheets may be varied by adjustment of the clamps 16 on the arms 11. For this purpose the arms 11 are graduated in distances from the axis of rotation. By thus adjusting the reeling bars 15 toward or away from the axis of rotation, the sheets may be cut in any desired lengths.

Having thus described my invention in such full, clear, and exact terms that its construction and operation will be readily understood by others skilled in the art to which it pertains, what I claim as new and desire to secure by Letters Patent of the United States is:

1. A winding reel including a pair of arms each secured to a spindle and projecting radially in opposite directions therefrom, a pair of bars each secured at its opposite extremities to said arms, a web spacer secured to said spindles and lying in a plane transverse to the plane of said bars, said reel and said web spacer being in permanently fixed angular relation, a clamp on said web spacer for securing thereto the free end portion of the material to be reeled, and a guide on said web spacer for the slidabale insertion of a cutting blade to cut the webs of the material into sheets.

2. A rotatable reel of rectangular form for reeling material from a roll, a web spacing bar rigidly

secured to said reel and transverse to the plane thereof, said reel and said web spacing bar having in common the axis of rotation, members having a loose connection at the corners of said reel to prevent binding of the material during the winding thereof, and a guide on said web spacing bar for the insertion of a cutting blade for guiding the sliding movement of a cutting blade to cut the webs of reeled material.

3. A winding reel including a pair of aligned spindles, a pair of arms secured to said spindles and projecting radially in opposite directions therefrom, a pair of clamps secured to each of said arms, said clamps being provided with sockets, and a pair of reeling bars each loosely seated at its end portions in the sockets of said clamps whereby the loose connection between said bars and said clamps will prevent binding action of the material on said reel.

4. A winding reel including a pair of aligned spindles, a pair of arms secured to said spindles and projecting in opposite directions therefrom, a pair of clamps secured to each of said arms for slidabale adjustment thereon, means for releasably securing said clamps in adjusted position on said arms, said clamps being provided with sockets, and a pair of reeling bars each loosely seated at its end portion in the sockets of said clamps whereby the loose connection between said bars and said clamps will prevent binding action of the sheet material on said reel.

5. A rotatable reel having lateral arms projecting radially in opposite directions from the axis of rotation of said reel, clamps slidably adjustable on said arms and means for securing said clamps in adjusted position, said clamps being provided with sockets, and a pair of reeling bars having their end portions loosely seated in the sockets of said clamps.

6. A reel winding device comprising a rotary reel element having spaced bars about which webs of material are wound during rotation of the reel, there being a transverse bar intermediate said spaced bars, said transverse bar having a portion adapted to project into the path of the webbing as it is wound about the reel whereby it be tightly engaged thereby, said portion being provided with a longitudinal notch forming a guideway into which a cutting tool may be inserted to cut the layers of webbing material while the webbing remains in tight engagement with said portion.

7. A winding reel comprising a spindle, arms projecting radially from the spindle, bars secured at their ends to said arms about which webbing may be wound, and a spacer element secured to the spindle, said spacer element having a portion adapted to project into the path of the webbing as it is wound on the reel to be tightly engaged thereby, and said portion being provided with a longitudinal groove forming a guide for a cutting tool to cut the webbing wound on the reel while the webbing remains in tight engagement with said portion.

SANDER DEBUS.
